LACQUERED METAL CONTAINER FOR
FOODSTUFFS

William Clayton, London, England, assignor to
Crosse and Blackwell Limited, London, Eng-
land, a British company

No Drawing. Application July 2, 1936, Serial No.
88,689. In Great Britain July 6, 1935

1 Claim. (Cl. 220—64)

The object of the present invention is to pro-
vide improved means for internally lacquering tin
plate containers.

This invention relates to an improved process
and apparatus for treating metal containers es-
pecially cans of tin plate.

When food products are preserved in metal
containers it is frequently necessary to protect
the metal from attack by coating the metal with
a lacquer. This coating is usually applied before
10 the metal sheet is formed into the can and, during
the mechanical processes necessary to form the
can, the lacquer film is liable to be ruptured, with
consequent exposure of the metal and danger of
15 subsequent corrosion.

According to the present invention I have
found that a metal container can be very effec-
tively protected against corrosion by lacquering
the inside of the said container by depositing the
lacquer electrophoretically from a lacquer emul-
20 sion of the oil-in-water type, the deposited film
being subsequently stoved if necessary.

The lacquers should be light coloured and
otherwise suitable for contact with foodstuffs,
25 and asphaltic or pitchy emulsions are thus un-
suitable.

A suitable emulsion is made from the usual
ingredients employed for lacquering food con-
tainers, e. g.

30 Linseed stand oil 175-200 lbs.
Synthetic resin 100 lbs.
Mn/Co drier (10:1) 1 lb. of metal as linoleate

Small amounts of a thinner such as turpentine
35 or white spirit may be added. 30 volumes of this
lacquer may be emulsified with 70 volumes of
water containing 0.25% NH₃ by weight as sta-
biliser.

The cans should be carefully cleaned and free
40 from grease. When a tinplate can holding 10

fluid ounces forms the anode, an initial current
of 2 amps. gives an effective deposit in about
5-10 seconds. After discharging the emulsion
and washing, the can may be stoved for 30 min-
utes at 380° F.

The volume of the disperse phase of the emul-
sion may be as high as 50% and the current
density may vary between wide limits, the higher
the current density the greater the rate of dep-
osition.

When using an aqueous medium which is alka-
line or oxidising, the invention has an important
advantage in that as a result of the electrical
treatment the tinplate gains an anodic protection
which is manifested in that the subsequent lac-
quer film no longer shows evidence of sulphide
10 stains on the plate below. For instance, certain
tinplates covered with the same lacquer, in the
one instance electro-deposited and in the other
with the usual mechanical rolling method, were 15
made into cans and filled with meat rolls. After
sterilisation and cooling, the cans were opened,
and whereas the can internally lacquered in the
usual way showed marked sulphide staining of
20 the plate beneath, the can lacquered electrically
was entirely free from such stain. According to
the invention, it is therefore possible to employ
a transparent lacquer for meat products and
other foods giving off sulphur compounds, in 25
place of the special lacquers hitherto employed
containing zinc oxide or other suspended matter.

I declare that what I claim is:

A container for foodstuffs formed from tin
plate, said container having the inner tin-coated 35
surface thereof anodically treated to prevent
staining, and a coating of transparent lacquer
electrophoretically deposited on and covering the
inner surface of said container.

WILLIAM CLAYTON. 40
